AIRPLANE ENGINE CONTROL

Milton E. Chandler, Detroit, Mich.

Application May 2, 1938, Serial No. 205,543

4 Claims. (Cl. 123—103)

This invention relates to the control of the throttle of an airplane engine. It is desirable in the control of an airplane engine that when the pilot has once determined the throttle position he requires for the speed at which he desires to climb, this speed be maintained at varying altitudes. Hence there should be a control which would automatically open the throttle as the plane climbs to a higher altitude. Therefore, the pressure created by the supercharger should be maintained at some constant figure. This control should be modified, however, by the fact that at higher altitudes, back pressure decreases and therefore, for a given pressure of the supercharger a greater horse power is formed at higher altitudes than at lower altitudes.

It is also desirable that the throttles should automatically assume the position for cruising whenever the control mechanism fails.

It is also desirable that the throttle should be in the proper position for re-starting after the engine has been stopped than it is when the ignition circuit has been opened.

It is desirable, too, to relieve the pilot of manual effort and for this purpose I propose to make use of the oil pressure created by an oil pump driven by the engine, and to supplement this oil pump by a manually operated oil pump.

In the drawings:

Figure 1 shows one form of my invention in which the carburetor and supercharger are indicated diagrammatically and the control device itself is shown in cross sectional elevation.

Figure 2 shows this device in elevation when viewed sideways.

Figure 3 shows a more elaborate control in which the device is located in the cockpit and the power is transmitted from the cockpit to the throttle hydraulically.

Describing Figure 1, 110 shows the entrance for the high pressure oil which is connected through an oil pipe 149 with the outlet from the oil pump 140. From the entrance 110 the oil flows immediately to an annular oil chamber 111 and from 111 it flows through the stationary sleeve 112 to an annular chamber 113. A movable inner sleeve 114 is mounted to slide inside the stationary sleeve 112 and is so formed as to control the ports 115 and 116 of the sleeve 112. For example, when the sleeve 114 is moved to the left from the neutral position illustrated, oil flows through the port 115 through the port 117, to the left hand side of the piston 118 in the cylindrical chamber 119.

The oil pressure acting on the left hand side

of the piston 118 pushes the throttle control rod 120 to the right and thus opens the throttle 129 through the following mechanism (see Figure 2):

The rod 120 engages with the pin 133 mounted on the bell crank lever 151. This bell crank lever is mounted on the pin 153 which, in its turn, is mounted on the bracket 169. This bell crank lever 151 is connected through the link 130 with the lever 147 which is mounted on the throttle shaft controlling the throttle 129. The throttle 10 is thus opened by the admission of the oil pressure to the left hand side of the piston 118. The movement of the sleeve 114 is controlled by a spring 121 and the pressure of this spring 121 in its turn, is controlled by the eccentric 122 which is controlled by the manually operated lever 123. When the lever 123 is moved to the right in a clockwise direction, the eccentric 122 is moved to the left. The pin 161 is thus moved to the left, carrying with it the lever 154 which has a fulcrum 155 which is mounted in the metallic element 156 carried by the evacuated bellows 157, which bellows contains the spring 158. This bellows is subjected to atmospheric pressure through the opening 159 in the cover 165.

In the event that it is desired not to correct the throttle opening for the back pressure variations with altitude, a set screw 160 is provided which will lock the piece 156 in place. Assuming, therefore, for the moment, that the fulcrum 155 is stationary, then as the throttle lever 123 moves to the right, the pin 161 moves to the left, and carries with it the pin 162 which pulls the spring housing 163 to the left. This reduces the pressure of the spring 121 on the valve 114. The valve 114 then moves to the left under the influence of a spring 125 contained in an evacuated bellows 124 which is mounted in the housing 126, which housing is provided with a cover 168. This housing communicates through the pipe 127 with the pressure side of the supercharger 128. Hence, having placed the throttle control lever in any given position, the variations in atmospheric pressure created by the supercharger move the valve 114 into the position 45 which will create a constant pressure in the supercharger 128. As the pressure of the atmosphere goes down, there is a tendency for the supercharger pressure to also decrease. Thus the spring 125 becomes more effective and the valve 114 moves to the left and the oil pressure is admitted through the port 115 and through the opening 146 through the port 117 to the left hand side of the piston 118.

If the reverse happens, and the plane descends

Remote controls

to sea level, when the atmospheric pressure increases, the supercharger pressure also increases. Therefore, the pressure in the housing 126 increases. The bellows 124 then collapses and the spring 121 pushes the valve 114 over to the right. Thereupon the port 116 is now put in communication with the annular chamber 113 and the oil pressure flows through an opening 145 in a tubular spacer through the port 143 to the right hand side of the piston 118 and the throttle rod 120 is returned to its original position. When that happens the port 115 is put in communication with the port 136 in the hollow valve 114. The oil then escapes from the left hand side 15 of the piston 118 through the port 117, through the port 146, through the port 115, through the port 136, through the port 137, through the chamber 138 in the casting 164 and so out through the return pipe 139 to the suction side of the oil pump 140.

When the piston 118 is moving to the right, the oil escapes from the chamber 119 through the port 143, through the port 145, through the port 116, through the port 144, through the hollow valve 114, through the port 137, into the chamber 138, and so, as before, out through the return pipe 139 to the suction side of the oil pump 140.

In order to provide a seal between the high pressure oil and the low pressure oil, four rubber grummets 171, 172, 173, 174 are provided at each end of the spacers carrying the ports 145 and 146. These grummets engage with the outer surface of the stationary sleeve 112. The left hand casting 164, the middle casting 166, and the right hand casting containing the chamber 126 and the bracket 169 are bolted together by bolts (not shown) and the four grummets 171, 172, 173 and 174 are thus compressed by the cylindrical spacers carrying the ports 146 and 145. Therefore, a tight joint is made preventing the oil leaking along the tube 112.

When the throttle is opened by the movement of the rod 120, the port 141 admits oil into the center of the hollow piston rod 120 as otherwise a vacuum would be formed therein. The leakage of oil past the rod 120 is limited by the spring loaded piston packing 170. Any leakage of oil into the chamber 126 is also limited by the spring load packing 167. Any oil which escapes by the valve 114 escapes down the port 135, the port 142, and so to the oil outlet 139. Any oil that escapes past the piston rod 120 also flows down the port 142 as it is prevented from escaping to the atmosphere by reason of the spring loaded packing 170 and also by the fact that the pump 140 maintains a suction through the pipe 139 in the port 142. Therefore, there is a tendency for the leakage to be inwards rather than outwards, and this is true of the chamber 126.

In an emergency it is desirable to take over the control by hand and to disengage the entire servo-mechanism from the throttle control linkage 151, 130, 147. To accomplish this conveniently, I provide (see Figure 2) a handle 132 on the bell crank lever 151. A spring 134 pulls the pivot 133 over to the right and holds the pin 133 in engagement with the slot 152 of the piston rod 120. If the lever 151 is slid over to the left the pin 133 is disengaged from the slot 152. Then the control of the throttle is taken away from the automatic hydraulic means shown 75 and the ordinary manual control takes its place.

In Figure 3 a more elaborate device is shown. Portions of the drawings are designated by the letters A, B, C and D. A corresponds to the 5 throttle control valve 114 and the controls therefor, shown in Figure 1; B corresponds to the piston 118, cylinder 119, and the piston rod 120 of Figure 1; C corresponds to the throttle controls 151, 130, 147; and D corresponds to the 10 oil pump 140 of Figure 1.

The pump 11 is intended to represent diagrammatically an engine driven oil pump. The other oil pump may be manually operated. The oil pump 11 and also the manually operated 15 pump deliver oil through the pipe 33 to the outside of the perforated sleeve 53. It then flows through an opening 54 in an inner sleeve 55. A movable tube 10 acts as the control valve and is provided with a conical face. This valve controls the communication of the high pressure oil from the pipe 33 to the port 42 in the sleeve 55. The valve 10 is adapted to be moved up and down, but when it is in the neutral position shown, the high pressure oil then has no access 25 through the opening 42 to the throttle control mechanism designated by the letter B.

When the valve 10 descends under the influence of the spring 108, the oil pressure causes oil to flow through this opening 42, through the 30 perforated sleeve 56, past the shut off valve 15 which is controlled by the manually operated lever 16. At this point, the oil may escape through a safety relief valve (not shown) which communicates with the outlet of the oil from 35 the valve 15 through a valve 43 controlled by a lever 44. This valve is shown closed and the valve 15 is shown open, which is the normal position. Under these circumstances, the oil may then take one of two paths—through the upper 40 pipe 17, or through the lower pipe 18. These pipes are of considerable length as the part designated by the letter A is adapted to be mounted in the cockpit adjacent to the pilot, whereas the part designated B is located on the engine adj- 45 to the throttle.

The reason for having two pipes is that if either of them breaks, the other is automatically disconnected without permitting any oil to escape. This is accomplished by means of two 50 identical valves 39, 39 which are balanced between similar springs 40, 40. If either pipe breaks the pressure in that pipe immediately falls and the valves 39 move in the direction of the broken pipe, sealing it off, and the other pipe 55 will then proceed to function as though no break had occurred.

When oil under pressure is admitted through the pipes 17 and 18 (Fig. 3) to the lower larger cylinder 36, the piston 21 immediately moves over to the right. This motion carries the piston rod 41 away from the stop 34 against which the piston 21 is pressed by the spring 22 and against which it is held firmly until the pressure on the piston 21 overcomes the pressure of the spring 22. An oil return pipe 76 insures that the oil pressure behind the piston 22 shall be low and removes the oil leaking past the piston 21.

When the oil pressure fails, the spring 22 immediately restores the piston 21 to its original 70 position, that is, with the piston rod 41 pressing against the stop 34. At the same time, the spring 24 in the upper smaller cylinder 66 acting on the smaller piston 23 attempts to move the piston rod 61 over to the left, so that the 75

piston 23 and its rod 61 could come to rest against a stop in the position shown. Through a link 48 the throttle lever 30 would thus be rotated in the counterclockwise direction to the open position shown in full, but it would be dangerous if on the failure of the oil pressure the engines were put into wide open throttle position, as the plane would then be unmanageable. To avoid this, it is necessary under such 10 circumstances to place the throttle in the cruising position.

This is insured by the following means: A pin 31 on the other end of the throttle lever 30 engages with a wide slot in the piston rod 41. Hence when the piston 21 moves to the left on the failure of the oil pressure, the throttle lever 30 is partially rotated, being pulled by the rod 41 acting against the pin 31 and against the action of the spring 24, until the throttle lever 30 assumes the position marked "Cruising" on Figure 3. To attain this result, it is necessary that the spring 22 be arranged to be more powerful than the spring 24, assuming that the lever arms of the lever 30 are equal. The plane then can be flown and landed with the throttle held in the cruising position automatically.

A broken vertical line will be noticed immediately to the right of the pin 31 when the pin 31 is in the cruising position. This indicates the position of the piston rod 41 when the piston rod 41 engages with the stop 34. When oil pressure is restored to the system, the larger piston 21 immediately assumes the position shown in the drawings (Figure 3) and the smaller piston assumes the position also shown in the drawings. This is the position for wide open throttle. As more and more oil pressure is admitted the piston 23 moves further and further to the right until at last it passes the cruising position and the throttle assumes idling position, when the pin 31 engages with the left hand wall of the slot in the piston rod 41. Under normal conditions, therefore, the movement of the piston 23 has complete control of the position of the throttle. 45 The larger piston 21 and its slotted piston rod 41 are merely provided for use in an emergency in the event that the oil pressure fails when by having this large piston 21 and the slotted piston rod 41 we can insure that the throttle is placed into the cruising position.

It will also be noticed that when the maximum pressure is admitted, the throttle is in the idle position so that excessive oil pressure cannot change the adjustment of the throttle, the intermediate positions of the throttle being controlled by reduction in oil pressure.

The control valve 10 is moved by the manually controlled lever 100 as follows: The lever 100 controls the eccentric 102 which raises the link 103 which, in its turn, raises the pin 50 and lever 49, as mentioned in the description of Figure 1. The clockwise movement of the manually controlled lever 100 thus reduces the pressure on the spring 108 and permits the valve 10 to rise under the influence of a spring 109 located in an exhausted bellows 46 located in the chamber 47 which communicates with the supercharger (not shown) through the pipe 14. The supercharger pressure in the chamber 47 acts on the exhausted bellows 46 mounted in the chamber 47. Hence when the pressure rises in 70 the valve 10 falls. Leakage of oil into the chamber 47 is prevented by the spring loaded packing 65. The oil pressure is allowed to escape from the cylinder 36 to the suction side of

the oil pump 11 when the valve 10 moves up under the influence of a decreased pressure in the chamber 47. The oil then escapes through the port 42, through a port 70 in the hollow valve 10. It then flows through the port 71 in the tube 55, through the passage 72 to the oil outlet 73, to the return pipe 74 to the suction side of the oil pumps 11. As before, in order to correct for the variations of back pressure, the exhausted bellows 106 is provided, supported internally by a spring 107 and mounted inside the hollow casting 62 which communicates with the atmosphere through the opening 101. This hollow bellows 106 carries the pin 105 which has an opening with which engages the ball 104 on 15 the end of the lever 49. Variations in atmospheric pressure thus control and modify the opening of the throttle lever 30. In the event that this refinement is unnecessary, a set screw 64 is provided so that this detail can be rendered inoperative.

In order to hold the pressure in the most desirable position for starting, that is to say, in a position half way between cruising and idling, the following device is provided. A solenoid 28 is connected in the ignition circuit through the terminals 27, 27. When the circuit is broken the solenoid no longer supports the rod 25 which descends under the influence of the spring 29 and engages with the slot 26 in the rod 61. The throttle will then be locked in a position in which the engine will reach about 800 R. P. M. which I have found the desirable throttle setting for restarting the engine.

In the event that the ignition is cut with the throttle in the idling position, that is to say, with the piston 23 over to the right, the pin 25 would then not engage with the slot 26. In that case the valve 43 is opened slightly and sufficient oil allowed to drain out to permit the piston 23 to move slightly to the left when the pin 25 drops into the slot 26 and the throttle is then held in this position regardless of any leakage of oil that may take place during the time the engine is not running.

The features to which my invention pertains are as follows:

A servo mechanism operated by oil pressure whereby the pilot can operate the throttle with the least possible effort.

A servo mechanism in which when the throttle control lever has been placed in any given position, the throttle will assume a corresponding position and will be held in that position by the pressure of the supercharger.

A servo mechanism in which, when the throttle control lever is placed in any given position during a climb the throttle will automatically open as the pressure of the atmosphere decreases, and as the atmospheric pressure increases during a descent, the throttle will be closed automatically.

Automatic means for correcting for the reduction in back pressure which causes a slight increase in power for the same supercharger pressure.

To provide means whereby the throttle automatically assumes the cruising position in the event that the servo mechanism fails due to any loss of oil pressure.

To insure that the throttles are held in the correct position for re-starting the engine after the ignition has been cut.

To provide means whereby the more or less delicate servo mechanism may be located in the

cockpit and the operating pistons of the throttle controls may be located on the carburetor and the operating pistons may be connected with the servo mechanism by means of two pipes, both transmitting hydraulic pressure to the operating pistons, and arranged so that either of them can break and the remaining pipe will continue to function despite the failure of the other pipe.

What I claim is:

- 10 1. In an airplane engine having an electric ignition system, an air entrance, a throttle valve therein, automatic throttle control means comprising a source of fluid pressure, a cylinder, a piston therein, means connecting said piston with said throttle, a slide valve, manual means for moving said slide valve, a port controlled by said slide valve communicating with said cylinder, said port being adapted to apply the fluid pressure to said cylinder to move said throttle, electro-magnetic means inoperative when the ignition system is operative, said electro-magnetic means being adapted when the ignition circuit is open to engage with said piston to hold said piston in a position in which the throttle is in the 15 position for starting the engine.
- 20 2. In an airplane engine having an air entrance, a throttle valve therein, automatic control means therefor comprising a source of fluid pressure, a throttle control lever, two cylinders, a piston in each cylinder, one piston having a one-way connection with said throttle lever, the other piston being permanently connected to the said throttle lever, a passage connecting the source of fluid pressure to said cylinders, manual 25 means for controlling the application of fluid pressure to said cylinders, the permanently connected piston being adapted to close the throttle on an increase in pressure, the other piston being adapted to close the throttle through the one-way connection to the cruising position on a 30 failure of the fluid pressure, and spring means adapted to move both pistons against the application of fluid pressure.
- 35 3. In an airplane engine having a supercharger, an air entrance leading thereto, a throttle valve therein, automatic means for operating the throttle valve comprising means responsive to the absolute pressure created by said supercharger, a slide valve adapted to be operated by said means, a spring also engaging with 40
- 45 50

said slide valve, manually operated means for varying the load on said spring, a cylinder, a piston therein, a port controlled by said slide valve communicating with said cylinder, means interconnecting the piston and the throttle, a source of oil pressure, said port being adapted to apply the oil pressure to said cylinder to move said throttle in one direction when the valve is in one position and to permit the oil to escape from said cylinder when the valve is in another position and in which the operating cylinder is located adjacent to the throttle valve and remote from said automatic throttle control means, and two pipes are provided connecting the throttle control means with the operative cylinder, spring loaded shut off valves located at each end of each of said connecting pipes, said valves being adapted to be held in the open position by the pressure in said pipes and to be closed by said springs on failure of the pressure.

4. In an airplane engine having a supercharger, an air entrance leading thereto, a throttle valve therein, automatic means for operating the throttle valve comprising means responsive to the absolute pressure created by said supercharger, a slide valve adapted to be operated by said means, a spring also engaging with said slide valve, manually operated means for varying the load on said spring, a cylinder, a piston therein, a port controlled by said slide valve communicating with said cylinder, means interconnecting the piston and the throttle, a source of oil pressure, said port being adapted to apply the oil pressure to said cylinder to move said throttle in one direction when the valve is in one position and to permit the oil to escape from said cylinder when the valve is in another position, an emergency control means comprising an auxiliary cylinder, said auxiliary cylinder being responsive to the oil pressure, a one-way connection between the piston rod and the throttle control, spring means for moving the piston against the action of the oil pressure, a one-way connection between the piston rod and the throttle control means adapted to close the throttle, whereby on failure of the oil pressure the throttle rod is automatically placed in the cruising position.

MILTON E. CHANDLER.
